UNITED STATES PATENT OFFICE

147,564

DESIGN FOR A PRECISION JEWELER'S VISE

Robert Alfred Nelson, Sherman Oaks, Calif.

Application May 6, 1946, Serial No. 129,377

Term of patent 3½ years

(CL. D54—14)

To all whom it may concern:

Be it known that I, Robert Alfred Nelson, a citizen of the United States, residing at Sherman Oaks, in the county of Los Angeles and State of California, have invented a new, original, and ornamental Design for a Precision Jeweler's Vise, of which the following is a specification, reference being had to the accompanying drawing, forming a part thereof.

Figure 1 is a side elevational view of a precision jeweler's vise, showing my new design.

Fig. 2 is a front elevational view thereof, with the vise handle moved 45° from that shown in Fig. 1.

Fig. 3 is a rear elevational view thereof.

Fig. 4 is a top plan view of the vise shown in Fig. 1.

I claim:

The ornamental design for a precision jeweler's vise, as shown.

ROBERT ALFRED NELSON.
